UNITED STATES PATENT OFFICE

153,991

DESIGN FOR A BOTTLE CAP FEEDER

Rudolph Sonnenberg, Belvidere, Ill., assignor to
Mid-West Bottle Cap Co., Belvidere, Ill., a cor-
poration of Illinois

Application September 15, 1947, Serial No. 141,406

Term of patent 14 years

(Cl. D2—3)

To all whom it may concern:

Be it known that I, Rudolph Sonnenberg, a citizen of the United States, residing at Belvidere, in the county of Boone and State of Illinois, have invented a new, original, and ornamental Design for a Bottle Cap Feeder, of which the following is a specification, reference being had to the accompanying drawings, forming part thereof.

In the drawings:

Figure 1 is a top view of a bottle cap feeder, showing my new design;

Figure 2 is a side elevational view thereof;

Figure 3 is a side elevational view taken at 90° with respect to Figure 2;

Figure 4 is a side elevational view of the side thereof opposite Figure 2, and

Figure 5 is a side elevation thereof opposite Figure 3.

I claim:

The ornamental design for a bottle cap feeder, substantially as shown.

RUDOLPH SONNENBERG.
